UNITED STATES PATENT OFFICE.

JOHN WILLIAM NASMITH, OF HEATON MERSEY, ENGLAND.

BANDING-MACHINE.

1,208,819.

Specification of Letters Patent. Patented Dec. 19, 1916.

Application filed February 8, 1912. Serial No. 676,365.

To all whom it may concern:

Be it known that I, JOHN WILLIAM NASMITH, of Heaton Mersey, Lancashire, England, have invented certain new and useful Improvements in Banding-Machines, of which the following is a specification.

This invention relates to apparatus for applying adhesive substances to bands of paper or the like and for feeding the said bands to boxes or other articles to be covered.

In apparatus of this kind, which will be hereinafter termed "banding machines", the band to be glued is drawn forward as required over a light roller immersed in the glue contained in a tank arranged below the roller. The paper is placed on the box or the like by hand, one side at a time, so that it is not usually drawn off continuously: while one face of the box is being covered the band is stationary, the box is then turned to bring another face into position when another length is drawn forward; the paper feed is therefore usually intermittent, and difficulty has been found in overcoming the inertia of the gluing roller, with the result that the band slipped forward over the surface of the gluing roller and a portion of the band failed to receive a sufficient quantity of glue. Efforts have been made to overcome this objection by dispensing with the usual stripping roller, but this is open to the objection that the band receives an unnecessary amount of adhesive most of which has to be removed by drawing the paper over scrapers, and the machine must therefore be made sufficiently long to allow of this and to allow the glued side of the band to be exposed long enough to dry partially before reaching the box.

The chief object of the present invention is to provide a banding machine in which the various objections mentioned above are overcome; other objects are to provide a banding machine in which the paper will not stick to the roller and the glue is not liable to dry upon the gluing roller when the machine is temporarily stopped, and in which waste of the paper or other band is avoided.

These and other features of the invention will now be described with reference to the accompanying drawings in which—

Figure 1 is a side elevation of one end of the improved banding machine. Fig. 2^a is a similar view of the opposite end of the ma-

chine. Fig. 2^b is a detail side elevation of the starting frame and its adjacent parts. Fig. 3 being a section of the same taken on the line 3—3 of Fig. 2^a, and Fig. 4, a plan 60 of same; and Fig. 5 is a plan; and Fig. 6 is a side elevation of a portion of yet another construction of banding machine according to my invention.

In Figs. 1 to 4 of the drawings there is 65 shown a construction of banding machine having means for driving the gluing roller positively. In the said figures the band A is shown passing from the roll A' over a guide roller D' mounted upon a bracket a, 70 under the roller C of the starting device, over the gluing roller B, under a guide roller D^a, and through the shearing apparatus S.

The machine is driven from the main 75 shaft G, which is mounted in suitable brackets g' carried by the main frame f and is driven continuously by a pulley g; the main shaft G also carries a beveled friction disk G' and a pulley G^a; the gluing roller B, and 80 consequently the paper feed, is driven from the pulley G^a, and the box-spindle is driven from the beveled disk G'.

The gluing roller is driven through a belt G^a, a pulley H, a friction disk H' running 85 with its periphery in contact with the faces of the pulley H and a disk H^a having a milled flange H^a, a disk J, a pinion J' (Fig. 3), and a pinion B^a; the pulley H is mounted upon a shaft h carried in bearings h^a 90 upon the main frame f of the machine and is pressed inward toward the disk H' by a spring h^a (Fig. 3); the intermediate disk H' is mounted upon a stud h' carried by an arm h^a pivoted upon a rod m that is adapted to slide in bearings m' mounted upon the main frame; the pulley is mounted upon the shaft h and is acted upon by the helical spring h^a threaded upon the shaft h between a collar h^a and the face of the bracket carrying the bearing h^a; and the disk J and the pinion J' are fixed on the opposite ends of a short shaft J^a carried in a boss at the lower end of the arm J^a of a two-armed lever J^a J^b fixed upon a shaft j carried in 105 a bracket j' and co-axial with the shaft b carrying the gluing roller, the disk J being—at the proper moment—adapted to come into contact with the milled flange H^a while the pinion J' is constantly in gear 110 with the pinion B^a, which is secured upon the shaft b carrying the gluing roller B.

The starting device consists of the roller C and a frame C¹⁰; this frame—of which only one arm is shown in Fig. 2^a—is secured upon a shaft C¹¹ pivoting in fixed bearings C¹² and carrying at one end a bar C¹³ which, since the other end of the frame is the heavier, rests normally against the underside of the bar M' of the main frame. A set-screw C⁵ is adjusted against the arm J⁴ of the lever J³ J⁴ so that the friction disk J is out of contact with the milled flange H^{2x}, this adjustment being effected against the action of a spring J⁵ secured at one end to the main frame and at the other to a rod J⁶ fitted with one end in a hole in the shaft j upon which the lever J³ J⁴ is fixed; the rod J⁶ is notched to facilitate the adjustment of the spring thereon, and by adjusting the spring upon the rod to give it the necessary tension, the system may be nicely balanced so that the weight of the roller C and the right-hand portion of the frame C¹⁰ acting through the set screw C⁵ and the arm J⁴ is just sufficient to keep the friction disk J out of contact with the revolving milled flange H^{2x}. When the end of the band A is pulled the roller C is raised, the frame C¹⁰ being rocked upward about its pivot C¹¹; this relieves the pressure, through the set-screw C⁵, of the starting device C C¹⁰ upon the arm J⁴ of the two-armed lever J³ J⁴ and allows the spring J⁵ to rock the said two-armed lever until the friction roller J comes into contact with the flange H^{2x} of the continuously driven disk H², with the result that motion is transmitted from the shaft G to the roller B through the various parts mentioned above.

The box-spindle N is driven, in the usual way, from the main shaft G through the beveled friction disk G', a similar disk L' on the side shaft L, a worm L² on the said shaft L, and a worm wheel N' mounted upon the box spindle: the beveled disk G' is at liberty to slide longitudinally upon a key fixed in the shaft G, and is normally out of contact with the beveled friction disk L' which is secured upon the shaft L, but upon the pedal G³ being pressed by the operator the disk G' is moved against the disk L' thus causing the spindle N to be rotated and with it the box or other articles around which the band is wrapped, the operator having previously drawn the free end of the band forward and stuck it to the end of the box, all in the usual manner.

To prevent more paper from being fed forward than is required for a single box, the position of the intermediate disk H' is adjusted relatively to the pulley H, by the longitudinal movement of the rod m, and the disk H² until the length delivered by the gluing roller B for each rotation of the box-spindle N corresponds to the sum of the length of the sides of each box being covered.

If the boxes are square or thereabout the speed of the box-spindle is practically regular, but when oblong boxes are being covered the said speed must vary from a maximum to a minimum twice during a revolution of the box, the maximum taking place when the long side of the box is passing vertically over the spindle N. To provide for this the box-spindle N is provided with a pinion N² gearing with a pinion N³ half the size of the pinion N² so that the pinion N³ revolves twice to the pinion N² once; across the face of the pinion N³ is a crank-member N⁴ provided with a slot N⁵ in which a stud N⁶ can be fixed at any desired distance from the center of the wheel N³ or on the center itself; and a connecting rod N⁷ is hinged on the stud N⁶ at one end and on a stud N⁸, attached to the sliding rod m, at the other end. By this mechanism the rod m will be moved to and fro twice while the box spindle N revolves once, consequently the friction disk H' will be moved to and fro between the pulley H and the disk H² and will accelerate and retard the speed of the latter to an extent that depends upon the eccentricity of the stud N⁶ which can be adjusted to suit the boxes being covered.

The roll of paper A' is carried on a shaft A³ and a light brake A⁴, pivoted at A⁵, is pressed by an adjustable weight A⁶. The roll of paper is thus prevented from overrunning, and also offers a slight resistance to the pull of the band, which is made sufficient to drive the gluing roller or lift the roller C as described.

Below the roller C of the starting appliance a transverse rod C³ is arranged, the band passing between the roller C and rod C³; a handle C⁴ is provided for the appliance and is loosely pivoted on the rod C¹³; by means of the handle C⁴ the starting-appliance frame C¹⁰ may be rocked into the position indicated by broken lines in Fig. 2^a when a notch C^{4x} engages with a pin M² on the main frame. When this is done the band A is moved entirely clear of the gluing roller B; the arm J⁴ of the lever J³ J⁴ is relieved of the weight of the starting appliance, and the spring J⁵ rocks the lever J³ J⁴ until the disk J comes into contact with the flange H^{2x} of the constantly rotating disk H², with the result that the gluing roller is rotated, and this rotation continues until the starting device C C¹⁰ is moved back to its normal position as indicated in full lines (Fig. 2^a). The moving of the band away from the gluing roller and the continuous rotation of the latter during a temporary stoppage of the machine prevents the band from becoming stuck to the gluing roller and the glue on the latter from becoming hard and cracking.

When the band A is being moved clear of the gluing roller B the friction disk J

swings into contact with the flange H^{2x} of the constantly rotating disk H^2 and the consequent rotation of the gluing roller B is liable, before the band can be moved out of contact therewith, to carry the band around with it and to produce a large loop on the forward side of the gluing roller B : to avoid this I may provide an extension J^{4x} of the arm J^4 and upon the shaft C^{11} a cam C^{110} adapted to act, for a short time, upon the extension J^{4x} when the arms C^{10} are rocked upward any considerable distance and to rock the arms J^3 in a counterclockwise direction until the disk J comes into contact with a brake shoe j^{10} mounted upon the frame P near to the glue tank. Therefore so long as the starting appliance C C^{10} is merely rocked by means of the band a sufficient distance to allow the arms J^3 to be rocked by the spring J^5 until the disk J bears upon the flange H^{2x} the cam C^{110} does not come into operation; but when the starting appliance is rocked a considerable distance by means of the handle C^4 , the cam comes into operation and acts upon the extension J^{4x} to cause the disk J to be swung into contact with the brake-block j^{10} and after the cam C^{110} , in turning with the arms C^{10} , has ceased to act upon the arm J^{4x} the spring J^5 pulls the arms J^3 back in order to cause the disk J to come into contact with the flange H^{2x} so that the gluing or adhesive-applying roller B will be driven continuously while the band is in the raised position indicated by broken lines in Fig. 2^a as described above. The brake j^{10} is also useful in that it brings the gluing roller B quickly to rest when a box has been covered; this is particularly necessary when large boxes are being covered, because in such case large lengths of band are drawn rapidly through the machine and the gluing and stripping rollers acquire so much momentum that they are liable to continue running even after the disk J has moved out of contact with the flange H^{2x} . By providing the brake block j^{10} the friction disk is stopped quickly immediately the tension on the band ceases and the starting appliance falls on to the arm J^4 . A glue tank F of ordinary construction is mounted upon the main frame P , and in it the gluing roller B is free to rotate upon its shaft b mounted in fixed bearings b' (Fig. 3); the spur wheel B^2 in addition to gearing with the pinion J' also gears with a spur wheel E' upon the shaft e of the stripping roller E ; and the shaft e is mounted in bearings e' which are adjustable by means of screws e^2 so that the distance between the rollers B and E can be adjusted with the utmost nicety in order that when they revolve only a thin film of adhesive material is carried over by the gluing roller B and deposited upon the band A .

Referring now to the construction shown

in Figs. 5 and 6; these figures illustrate an apparatus for simultaneously gluing a main band, which may be plain and comparatively wide, and two comparatively narrow border bands. In this construction the glue tank T is extended, the usual (or primary) gluing roller B is employed for the main band, and there is provided a secondary gluing roller B^x over which the border bands (one of which is indicated by A^x in Fig. 6) are drawn from rolls that turn about an axis or axes parallel to the axis of the roll from which the main band is drawn. The border-bands are so arranged longitudinally upon the second gluing roller that when all of the bands are drawn together under the guide roller D^2 (after leaving the gluing rollers) they have the required amount of overlap without adjustment by guides or the like.

The gluing rollers B , B^x are geared together by spur wheels B^2 , E' , k , k' , and B^{2x} so as to be capable of both being driven positively as described above in connection with the apparatus shown in Figs. 2 to 4, and the gluing roller B^x is provided with a band-engaging device C^x similar to the device C , C^3 , C^{10} , C^{11} shown in Figs. 2 and 4 and connected to the latter device by a link R whereby, when the machine is temporarily stopped, all of the said bands may be simultaneously moved away from the gluing rollers B , B^x while the latter are rotated as and for the purposes set out above.

The intermediary gear wheels k , k' are equal in size and are mounted upon shafts carried in bearings upon a pair of brackets (K) mounted upon the frame of the machine as shown in the drawings.

The rod or link R is connected to the appliance C^x by means of a slot R' with which a pin b^x engages so as to allow of a certain amount of relative movement between the two appliances, since the appliance C , C^{10} , etc., acts as a starting appliance.

One of the arms of the supplementary appliance C^x is provided with an extension C^{15} adapted to rest upon the edge of the glue tank or upon a bracket connected thereto and to act as a stop to determine the position of the said appliance. The arms of the said supplementary appliance are pivoted at C^{11x} upon the bracket K .

An adjustable guide roller D^2 is mounted by means of a slotted bracket upon pins on the glue tank T , as shown in Fig. 6.

The secondary gluing roller B^x is provided with a stripping roller E^x which is geared to the roller B^x by means of a spur wheel E'^x meshing with the wheel B^{2x} .

Having now described my invention, what I claim and desire to secure by Letters Patent in the United States is:—

1. In a banding machine, the combination with a receptacle for an adhesive, of a ro-

tatable adhesive applying roller in contact with the adhesive in said receptacle, continuously driven means for imparting rotation to said adhesive applying roller, and 5 means intermediate said adhesive-applying roller and said continuously driven means under the control of the band for imparting rotation to said adhesive-applying roller.

2. In a banding machine, the combination 10 with a receptacle for an adhesive, of a rotatable adhesive applying roller in contact with the adhesive in said receptacle, continuously driven means for imparting rotation to said adhesive applying roller, and 15 normally inactive means intermediate said adhesive-applying roller and said continuously driven means under the control of the band for imparting rotation to said adhesive applying roller.

20 3. In a banding machine, the combination with a receptacle for an adhesive, of a rotatable adhesive-applying roller in contact with the adhesive in said receptacle, continuously driven means for imparting rotation 25 to said adhesive applying roller, means intermediate said adhesive-applying roller and said continuously driven means for imparting rotation to said adhesive applying roller, means to normally maintain said intermediate device inactive, and means under 30 the control of the band for releasing said intermediate means and imparting rotation to said adhesive-applying roller.

4. In a banding machine, the combination 35 with a receptacle for an adhesive, of a rotatable adhesive applying roller in contact with the adhesive in said receptacle, continuously driven means for imparting rotation to said adhesive applying roller, a roller intermediate 40 said adhesive applying roller and said continuously driven means for imparting rotation to said adhesive-applying roller, means for normally maintaining said intermediate roller out of contact with said 45 continuously driven means, and means under the control of the band for releasing said intermediate roller and to permit contact with said continuously driven means.

5. In a banding machine the combination 50 of a receptacle for the adhesive substance; an adhesive-applying roller partly immersed in the contents of the receptacle and adapted to be rotated therein; a stripping roller adapted to rotate with its peripheral 55 face clear of the adhesive in the receptacle and a short distance from the adhesive-applying roller; means for positively driving the adhesive-applying roller; means, acted upon by the band, for bringing the said 60 positive driving means into operation; and means for positively driving the stripping roller simultaneously with the driving of the adhesive-applying roller.

6. In a banding machine the combination 65 of a receptacle for the adhesive substance;

an adhesive-applying roller partly immersed in the contents of the receptacle and adapted to be rotated therein; means for positively and continuously driving the adhesive-applying roller; means, acted upon by the band, for bringing the said positive driving means into operation; and means for engaging with the band said means being adapted to lift the band clear of the adhesive-applying roller. 75

7. In a banding machine the combination of a receptacle for the adhesive substance; an adhesive-applying roller partly immersed in the contents of the receptacle and adapted to be rotated therein; a stripping roller 80 adapted to rotate with its peripheral face clear of the adhesive in the receptacle and a short distance from the adhesive-applying roller; means for positively driving the adhesive-applying roller; means, acted upon by the band, for bringing the said positive driving means into operation; means for positively driving the stripping roller simultaneously with the driving of the adhesive-applying roller; and means for engaging 85 with the band said means being adapted to lift the band clear of the adhesive-applying roller. 90

8. In a banding machine the combination 95 of a receptacle for the adhesive substance; an adhesive-applying roller partly immersed in the contents of the receptacle and adapted to be rotated therein; means for positively driving the adhesive-applying roller; means, acted upon by the band, for bringing the said positive driving means into operation; and means for varying the speed of the adhesive-applying roller in accordance with the size of the article being covered. 100

9. In a banding machine the combination 105 of a receptacle for the adhesive substance; an adhesive-applying roller partly immersed in the contents of the receptacle and adapted to be rotated therein; means for positively driving the adhesive-applying roller; means, acted upon by the band, for bringing the said positive driving means into operation; means for varying the speed of the adhesive-applying roller in accordance with the size of the article being covered; and 110 means for engaging with the band said means being adapted to lift the band clear of the adhesive-applying roller. 115

10. In a banding machine the combination 120 of a receptacle for the adhesive substance; an adhesive-applying roller partly immersed in the contents of the receptacle and adapted to be rotated therein; a stripping roller adapted to rotate with its peripheral face clear of the adhesive in the receptacle 125 and a short distance from the adhesive-applying roller; means for positively driving the adhesive-applying roller; means, acted upon by the band, for bringing the said positive driving means into operation; means 130

for positively driving the stripping roller simultaneously with the driving of the adhesive-applying roller; and means for varying the speed of the adhesive-applying roller in accordance with the size of the article being covered.

11. In a banding machine the combination of a receptacle for the adhesive substance; an adhesive-applying roller partly immersed in the contents of the receptacle and adapted to be rotated therein; a stripping roller adapted to rotate with its peripheral face clear of the adhesive in the receptacle and a short distance from the adhesive-applying roller; means for positively driving the adhesive-applying roller; means, acted upon by the band, for bringing the said positive driving means into operation; means for positively driving the stripping roller simultaneously with the driving of the adhesive-applying roller; means for varying the speed of the adhesive-applying roller in accordance with the size of the article being covered; and means for engaging with the band said means being adapted to lift the band clear of the adhesive-applying roller.

12. In a banding machine the combination of a receptacle for the adhesive substance; an adhesive-applying roller partly immersed in the contents of the receptacle and adapted to be rotated therein; means for positively driving the adhesive-applying roller; means, acted upon by the band, for bringing the said positive driving means into operation; and means whereby the speed of the adhesive-applying roller is varied, during the covering of each article, in accordance with the sizes of the sides of the article being covered.

13. In a banding machine the combination of a receptacle for the adhesive substance; an adhesive-applying roller partly immersed in the contents of the receptacle and adapted to be rotated therein; means for positively driving the adhesive-applying roller; means, acted upon by the band, for bringing the said positive driving means into operation; means whereby the speed of the adhesive-applying roller is varied, during the covering of each article, in accordance with the sizes of the sides of the article being covered; and means for engaging with the band said means being adapted to lift the band clear of the adhesive-applying roller.

14. In a banding machine the combination of a receptacle for the adhesive substance; an adhesive-applying roller partly immersed in the contents of the receptacle and adapted to be rotated therein; a stripping roller adapted to rotate with its peripheral face clear of the adhesive in the receptacle and a short distance from the adhesive-applying roller; means for positively driving the adhesive-applying roller; means, acted upon by the band, for bringing the said positive driving means into operation;

driving means into operation; means for positively driving the stripping roller simultaneously with the driving of the adhesive-applying roller; and means whereby the speed of the adhesive-applying roller is varied, during the covering of each article, in accordance with the sizes of the sides of the article being covered.

15. In a banding machine the combination of a receptacle for the adhesive substance; an adhesive-applying roller partly immersed in the contents of the receptacle and adapted to be rotated therein; a stripping roller adapted to rotate with its peripheral face clear of the adhesive in the receptacle and a short distance from the adhesive-applying roller; means for positively driving the adhesive-applying roller; means, acted upon by the band, for bringing the said positive driving means into operation; means for positively driving the stripping roller simultaneously with the driving of the adhesive-applying roller; means whereby the speed of the adhesive-applying roller is varied, during the covering of each article, in accordance with the sizes of the sides of the article being covered; and means for engaging with the band said means being adapted to lift the band clear of the adhesive-applying roller.

16. In a banding machine the combination of a receptacle for the adhesive substance; an adhesive-applying roller partly immersed in the contents of the receptacle and adapted to be rotated therein; means for positively driving the adhesive-applying roller; means, acted upon by the band, for bringing the said positive driving means into operation; means for varying the speed of the adhesive-applying roller in accordance with the size of the article being covered; and means whereby the speed of the adhesive-applying roller is varied, during the covering of each article, in accordance with the sizes of the sides of the article being covered.

17. In a banding machine the combination of a receptacle for the adhesive substance; an adhesive-applying roller partly immersed in the contents of the receptacle and adapted to be rotated therein; means for positively driving the adhesive-applying roller; means, acted upon by the band, for bringing the said positive driving means into operation; means for varying the speed of the adhesive-applying roller in accordance with the size of the article being covered, means whereby the speed of the adhesive-applying roller is varied, during the covering of each article, in accordance with the sizes of the sides of the article being covered; and means for engaging with the band said means being adapted to lift the band clear of the adhesive-applying roller.

18. In a banding machine the combination of a receptacle for the adhesive substance;

an adhesive-applying roller partly immersed in the contents of the receptacle and adapted to be rotated therein; a stripping roller adapted to rotate with its peripheral face 5 clear of the adhesive in the receptacle and a short distance from the adhesive-applying roller; means for positively driving the adhesive-applying roller; means, acted upon by the band, for bringing the said positive 10 driving means into operation; means for positively driving the stripping roller simultaneously with the driving of the adhesive-applying roller; means for varying the speed of the adhesive-applying roller in accordance with the size of the article being 15 covered; and means whereby the speed of the adhesive-applying roller is varied, during the covering of each article, in accordance with the sizes of the sides of the article 20 being covered.

19. In a banding machine the combination of a receptacle for the adhesive substance; an adhesive-applying roller partly immersed in the contents of the receptacle and adapted 25 to be rotated therein; a stripping roller adapted to rotate with its peripheral face clear of the adhesive in the receptacle and a short distance from the adhesive-applying roller; means for positively driving the adhesive-applying roller; means, acted upon 30 by the band, for bringing the said positive driving means into operation; means for positively driving the stripping roller simultaneously with the driving of the adhesive-applying roller; means for varying the speed of the adhesive-applying roller in accordance 35 with the size of the article being covered; means whereby the speed of the adhesive-applying roller is varied, during the covering of each article, in accordance with the sizes of the sides of the article 40 being covered; and means for engaging with the band said means being adapted to lift the band clear of the adhesive-applying roller.

45 20. In a banding machine the combination of a main frame; a receptacle for an adhesive substance said receptacle being mounted upon the main frame; an adhesive-applying roller partly immersed in the contents of the receptacle and adapted to be rotated therein; a starting device comprising arms pivotally mounted upon the main frame, and means, carried by the arms, for engaging with the band; a rotatable member 50 mounted upon the main frame; means for imparting continuous motion to the said member; and intermediate mechanism for transmitting motion from the continuously rotating member to the adhesive-applying roller, the said intermediate mechanism being brought into operative position when the starting device is rocked through a pull upon the band; and means for varying, during the covering of each article, the speed transmitted from the continuously rotating member 55 to the adhesive-applying roller.

60 21. In a banding machine the combination of a main frame; a receptacle for an ad-

hesive substance said receptacle being mounted upon the main frame; an adhesive-applying roller partly immersed in the contents of the receptacle and adapted to be rotated therein; a starting device comprising arms 70 pivotally mounted upon the main frame, means, carried by the arms, for engaging with the band; a rotatable member mounted upon the main frame; means for imparting continuous motion to the said member; intermediate mechanism for transmitting motion from the continuously rotating member to the adhesive-applying roller, the said intermediate mechanism being brought into operative position when the starting device 75 is rocked through a pull upon the band; and means for varying the speed transmitted from the continuously rotating member to the adhesive-applying roller.

22. In a banding machine the combination of a main frame; a receptacle for an adhesive substance said receptacle being mounted upon the main frame; an adhesive-applying roller partly immersed in the contents of the receptacle and adapted to be rotated therein; a starting device comprising arms pivotally mounted upon the main frame, means, carried by the arms, for engaging with the band; a rotatable member mounted upon the main frame; means for imparting continuous motion to the said member; intermediate mechanism for transmitting motion from the continuously rotating member to the adhesive-applying roller, the said intermediate mechanism being 90 brought into operative position when the starting device is rocked through a pull upon the band; and means for varying, during the covering of each article, the speed transmitted from the continuously rotating member 95 to the adhesive-applying roller.

23. In a banding machine the combination of a main frame; a receptacle for an adhesive substance, said receptacle being mounted upon the main frame; an adhesive-applying roller and bearings carried by the main frame in which the adhesive-applying roller is mounted so as to be partly immersed in the adhesive substance contained in the receptacle; a stripping roller and bearings in 110 which the stripping roller is adapted to rotate with its peripheral face clear of the adhesive substance in the receptacle and with its axis parallel to the axis of the adhesive-applying roller, the said bearings being adjustable toward and away from the adhesive-applying roller; a starting device comprising arms pivotally mounted upon the main frame, means, carried by the arms, for engaging with the band; a rotatable member 115 mounted upon the main frame; means for imparting continuous motion to the said member; intermediate mechanism for transmitting motion from the continuously rotating member to the adhesive-applying roller; a starting device comprising arms pivotally mounted upon the main frame, means, carried by the arms, for engaging with the band; a rotatable member 120 mounted upon the main frame; means for imparting continuous motion to the said member; intermediate mechanism for transmitting motion from the continuously rotating member to the adhesive-applying roller, 125 130

the said intermediate mechanism being brought into operative position when the starting device is rocked through a pull upon the band; and means for positively driving 5 the stripping roller simultaneously with the driving of the adhesive-applying roller.

24. In a banding machine the combination of a main frame; a receptacle for an adhesive substance said receptacle being 10 mounted upon the main frame; an adhesive-applying roller partly immersed in the contents of the receptacle and adapted to be rotated therein; a starting device comprising arms pivotally mounted upon the main frame, means, carried by the arms, for engaging 15 with the band; a friction disk rotatably mounted upon the main frame; means for driving the said friction disk continuously at a uniform speed; a differential 20 disk mounted with its face opposite that of the uniformly driven disk; an intermediate disk adapted to run with its periphery in contact with the adjacent faces of the differential and the uniformly driven 25 disks and to transmit rotary motion from the latter to the former the said intermediate disk being adjustable radially of the two contacting disks; and intermediate mechanism for transmitting rotary motion 30 from the differential disk to the adhesive-applying roller, the said intermediate mechanism being brought into operative position by the rocking of the starting device when the band is pulled forward.

25. In a banding machine the combination of a main frame; a receptacle for an adhesive substance said receptacle being mounted upon the main frame; an adhesive-applying roller partly immersed in the contents of the receptacle and adapted to be rotated therein; a starting device comprising arms pivotally mounted upon the main frame and means, carried by the arms, for engaging 40 with the band; a friction disk rotatably mounted upon the main frame; means for driving the said friction disk continuously at a uniform speed; a differential disk mounted upon the main frame to rotate with its face opposite that of the uniformly driven disk; an intermediate disk 45 rotatably mounted upon the main frame; means for driving the said friction disk continuously at a uniform speed; a differential disk mounted upon the main frame to rotate with its face opposite that of the uniformly driven disk; an intermediate disk adapted to run with its periphery in contact with the adjacent faces of the differential and the uniformly driven disks and to transmit rotary motion 50 from the latter to the former the said intermediate disk being adjustable radially of the two contacting disks; and intermediate mechanism for transmitting rotary motion from the differential disk to the adhesive applying roller the said intermediate mechanism comprising a swinging frame upon which the starting device rests, a gear wheel carried by the said frame, and means whereby, when the starting appliance is moved upon 55 the end of the band being pulled, the said

frame is swung to bring its gear wheel into engagement with other units of the intermediate mechanism to complete the train between the differential disk and the adhesive-applying roller.

26. In a banding machine the combination of a main frame; a receptacle for the adhesive substance; an adhesive-applying roller partly immersed in the contents of the receptacle and adapted to be rotated 70 therein; a starting device comprising arms pivotally mounted upon the main frame and means, carried by the arms, for engaging with the band; a rotatable member mounted upon the main frame; means for imparting continuous motion to the said member; and intermediate mechanism for transmitting rotary motion from the continuously driven member to the adhesive-applying roller the said intermediate mechanism comprising a swinging frame upon which the starting device rests, a gear wheel carried by the said swinging frame, and means whereby when the starting device is 75 rocked through the pulling of the band end 80 the gear-carrying frame is swung into engagement with other units of the intermediate gear to complete the train of gearing between the continuously driven member and the adhesive-applying roller.

27. In a banding machine the combination of a main frame; a receptacle for an adhesive substance said receptacle being mounted upon the main frame; a stripping roller adapted to rotate with its peripheral face clear of the adhesive in the receptacle and a short distance from the adhesive-applying roller; a starting device comprising arms pivotally mounted upon the main frame, and means, carried by the arms, for engaging 100 with the band; a friction disk rotatably mounted upon the main frame; means for driving the said friction disk continuously 105 at a uniform speed; a differential disk mounted upon the main frame to rotate with its face opposite that of the uniformly driven disk; an intermediate disk adapted to run with its periphery in contact with the adjacent faces of the differential and the uniformly driven disks and to transmit rotary motion 110 from the latter to the former the said intermediate disk being adjustable radially of the two contacting disks; intermediate mechanism for transmitting rotary motion from the differential disk to the adhesive-applying roller, the said intermediate mechanism being brought into operative position by the rocking of the starting device when the band is pulled forward; a rotatable support for the article to be covered; means for driving the said support; and means whereby the position of the intermediate disk is regulated automatically 115 from the support for the article so that the speed transmitted to the adhesive applying 120 roller

roller varies in accordance with the length of the side of the article being covered.

28. In a banding machine the combination of a main frame; a receptacle for an adhesive substance said receptacle being mounted upon the main frame; an adhesive-applying roller partly immersed in the contents of the receptacle and adapted to be rotated therein; a starting device comprising arms pivotally mounted upon the main frame and means, carried by the arms, for engaging with the band; a friction disk rotatably mounted upon the main frame; means for driving the said friction disk continuously at a uniform speed; a differential disk mounted upon the main frame to rotate with its face opposite that of the uniformly driven disk; an intermediate disk adapted to run with its periphery in contact with the adjacent faces of the differential and the uniformly driven disks and to transmit rotary motion from the latter to the former the said intermediate disk being adjustable radially of the two contacting disks; intermediate mechanism for transmitting rotary motion from the differential disk to the adhesive applying roller the said intermediate mechanism comprising a swinging frame upon which the starting device rests, a gear wheel carried by the said swinging frame, and means whereby, when the starting appliance is moved upon the end of the band being pulled, the gear-carrying frame is swung into engagement with other units of the intermediate mechanism to complete the train between the differential disk and the adhesive-applying roller; a rotatable support for the article to be covered; means for driving the said support; and means whereby the position of the intermediate disk is regulated automatically from the support for the article so that the speed transmitted to the adhesive applying roller varies in accordance with the length of the side of the article being covered.

29. In a banding machine the combination of a main frame; a receptacle for an adhesive substance said receptacle being mounted upon the main frame; an adhesive-applying roller partly immersed in the contents of the receptacle and adapted to be rotated therein; a friction disk rotatably mounted upon the main frame; means for driving the said friction disk continuously at a uniform speed; a differential disk mounted upon the main frame to rotate with its face opposite that of the uniformly driven disk; an intermediate disk adapted to run with its periphery in contact with the adjacent faces of the differential and the uniformly driven disks and to transmit rotary motion from the latter to the former, a bracket upon which the said intermediate disk is mounted, a rod upon which the said bracket is mounted, bearings carried upon the main frame and in which

said rod is adapted to slide; a rotatable support for the article to be covered; means for driving the said support; an arm mounted upon said support; and a connecting-rod adjustably secured at one end to the arm and at the other to the sliding rod that carries the bracket in which the intermediate disk is mounted.

30. In a banding machine the combination of a main frame; a receptacle for an adhesive substance said receptacle being mounted upon the main frame; an adhesive-applying roller partly immersed in the contents of the receptacle and adapted to be rotated therein; a starting device comprising arms pivotally mounted upon the main frame and means, carried by the arms, for engaging with the band; a friction disk rotatably mounted upon the main frame; means for driving the said friction disk continuously at a uniform speed; a differential disk mounted upon the main frame to rotate with its face opposite that of the uniformly driven disk; an intermediate disk adapted to run with its periphery in contact with the adjacent faces of the differential and the uniformly driven disks and to transmit rotary motion from the latter to the former a bracket upon which the said intermediate disk is mounted, a rod upon which the said bracket is mounted, bearings carried upon the main frame and in which said rod is adapted to slide; intermediate mechanism for transmitting rotary motion from the differential disk to the adhesive applying roller the said intermediate mechanism comprising a swinging frame upon which the starting device rests, a gear wheel carried by the said swinging frame, and means whereby, when the starting appliance is moved upon the end of the band being pulled, the gear carrying frame is swung into engagement with other units of the intermediate mechanism to complete the train between the differential disk and the adhesive-applying roller; a rotatable support for the article to be covered; means for driving the said support; and means whereby the position of the intermediate disk is regulated automatically from the support for the article so that the speed transmitted to the adhesive applying roller varies in accordance with the length of the side of the article being covered.

31. In a banding machine the combination of a main frame; a receptacle for an adhesive substance said receptacle being mounted upon the main frame; an adhesive-applying roller partly immersed in the contents of the receptacle and adapted to be rotated therein; a starting device comprising arms pivotally mounted upon the main frame, means, carried by the arms, for engaging with the band; a friction disk rotatably mounted upon the main frame; means for driving the said friction disk continuously at the uniform speed; a differential disk mounted

upon the main frame to rotate with its face opposite that of the uniformly driven disk; an intermediate disk adapted to run with its periphery in contact with the adjacent faces of the differential and the uniformly driven disks and to transmit rotary motion from the latter to the former the said intermediate disk being adjustable radially of the two contacting disks; and intermediate mechanism for transmitting rotary motion from the differential disk to the adhesive applying roller the said intermediate mechanism comprising a gear wheel carried by a swinging frame upon which the starting device rests and adjustable means whereby when the band is not being pulled forward the weight of the starting appliance upon the swinging frame is balanced and the said frame held in a position in which its gear wheel is inoperative but upon the band being pulled forward and the starting device lifted the gear carrying frame is swung into engagement with other units of the intermediate mechanism to complete the train of gearing between the differential disk and the adhesive applying roller.

32. In a banding machine the combination of a main frame; a receptacle for an adhesive substance said receptacle being mounted upon the main frame; an adhesive-applying roller partly immersed in the contents of the receptacle and adapted to be rotated therein; a starting device comprising arms pivotally mounted upon the main frame, means, carried by the arms, for engaging with the band; a rotatable member mounted upon the main frame; means for imparting continuous motion to the said member; and intermediate mechanism for transmitting motion from the continuously rotating member to the adhesive-applying roller the said intermediate mechanism comprising a gear wheel carried by a swinging frame upon which the starting device rests, and adjustable means whereby when the band is not being pulled forward the weight of the starting device upon the swinging frame is balanced and the said frame held in a position in which its gear wheel is inoperative but upon the band being pulled forward and the starting device lifted the gear carrying frame is swung into engagement with other units of the intermediate mechanism to complete the train of gearing between the continuously rotating member and the adhesive-applying roller.

33. In a banding machine the combination of a receptacle for the adhesive substance; an adhesive-applying roller partly immersed in the contents of the receptacle and adapted to be rotated therein; means for positively and continuously driving the adhesive-applying roller; means, acted upon by the band, for bringing the said positive driving means into operation; and means for bring-

ing the adhesive-applying roller quickly to rest.

34. In a banding machine the combination of a receptacle for the adhesive substance; an adhesive-applying roller partly immersed in the contents of the receptacle and adapted to be rotated therein; means for positively driving the adhesive-applying roller; means, acted upon by the band, for bringing the said positive driving means into operation; means for engaging with the band said means being adapted to lift the band clear of the adhesive-applying roller; and means for preventing the positive driving-mechanism from operating while the band is being lifted clear of the adhesive-applying roller. 75 80

35. In a banding machine the combination of a receptacle for the adhesive substance; an adhesive-applying roller partly immersed in the contents of the receptacle and adapted to be rotated therein; means for positively driving the adhesive-applying roller; means, acted upon by the band, for bringing the said positively driving means into operation; means for varying the speed of the adhesive-applying roller in accordance with the size of the article being covered; and means for bringing the adhesive-applying roller quickly to rest. 85 90

36. In a banding machine the combination of a receptacle for the adhesive substance; an adhesive-applying roller partly immersed in the contents of the receptacle and adapted to be rotated therein; means for positively driving the adhesive-applying roller; means, acted upon by the band, for bringing the said positive driving means into operation; means for varying the speed of the adhesive-applying roller in accordance with the size of the article being covered; means for engaging with the band said means being adapted to lift the band clear of the adhesive-applying roller; and means for bringing the adhesive-applying roller quickly to rest. 95 100 105

37. In a banding machine the combination of a receptacle for the adhesive substance; an adhesive-applying roller partly immersed in the contents of the receptacle and adapted to be rotated therein; a stripping roller adapted to rotate with its peripheral face clear of the adhesive in the receptacle and a short distance from the adhesive-applying roller; means for positively driving the adhesive-applying roller; means, acted upon by the band, for bringing the said positive driving means into operation; means for positively driving the stripping roller simultaneously with the driving of the adhesive-applying roller; means for varying the speed of the adhesive-applying roller in accordance with the size of the article being covered; means for engaging with the band said means being adapted to lift the band clear of the adhesive-applying roller; and 110 115 120 125 130

means for preventing the positive driving-mechanism from operating while the band is being lifted clear of the adhesive-applying roller.

38. In a banding machine the combination of a receptacle for the adhesive substance; an adhesive-applying roller partly immersed in the contents of the receptacle and adapted to be rotated therein; means for positively driving the adhesive-applying roller; means, acted upon by the band, for bringing the said positive driving means into operation; means whereby the speed of the adhesive-applying roller is varied, during the covering of each article, in accordance with the sizes of the sides of the article being covered; and means for bringing the adhesive-applying roller quickly to rest.

39. In a banding machine the combination of a receptacle for the adhesive substance; an adhesive-applying roller partly immersed in the contents of the receptacle and adapted to be rotated therein; means for positively driving the adhesive-applying roller; means, acted upon by the band, for bringing the said positive driving means into operation; means whereby the speed of the adhesive-applying roller is varied, during the covering of each article, in accordance with the sizes of the sides of the article being covered; means for engaging with the band said means being adapted to lift the band clear of the adhesive-applying roller; and means for preventing the positive driving-mechanism from operating while the band is being lifted clear of the adhesive-applying roller.

40. In a banding machine the combination of a receptacle for the adhesive substance; an adhesive-applying roller partly immersed in the contents of the receptacle and adapted to be rotated therein; a stripping roller adapted to rotate with its peripheral face clear of the adhesive in the receptacle and a short distance from the adhesive-applying roller; means for positively driving the adhesive-applying roller; means, acted upon by the band, for bringing the said positive driving means into operation; means for positively driving the stripping roller simultaneously with the driving of the adhesive-applying roller; means whereby the speed of the adhesive-applying roller is varied, during the covering of each article, in accordance with the sizes of the sides of the article being covered; means for engaging with the band said means being adapted to lift the band clear of the adhesive-applying roller; and means for preventing the positive driving-mechanism from operating while the band is being lifted clear of the adhesive-applying roller.

41. In a banding machine the combination of a receptacle for the adhesive substance; an adhesive-applying roller partly immersed

in the contents of the receptacle and adapted to be rotated therein; means for positively driving the adhesive-applying roller; means, acted upon by the band, for bringing the said positive driving means into operation; means for varying the speed of the adhesive-applying roller in accordance with the size of the article being covered; means whereby the speed of the adhesive-applying roller is varied, during the covering of each article, in accordance with the sizes of the sides of the article being covered; and means for bringing the adhesive-applying roller quickly to rest.

42. In a banding machine the combination of a receptacle for the adhesive substance; an adhesive-applying roller partly immersed in the contents of the receptacle and adapted to be rotated therein; means for positively driving the adhesive-applying roller; means, acted upon by the band, for bringing the said positive driving means into operation; means for varying the speed of the adhesive-applying roller in accordance with the size of the article being covered, means whereby the speed of the adhesive-applying roller is varied, during the covering of each article, in accordance with the sizes of the sides of the article being covered; means for engaging with the band said means being adapted to lift the band clear of the adhesive-applying roller; and means for preventing the positive driving-mechanism from operating while the band is being lifted clear of the adhesive applying roller.

43. In a banding machine the combination of a receptacle for the adhesive substance; an adhesive-applying roller partly immersed in the contents of the receptacle and adapted to be rotated therein; a stripping roller adapted to rotate with its peripheral face clear of the adhesive in the receptacle and a short distance from the adhesive-applying roller; means for positively driving the adhesive-applying roller; means, acted upon by the band, for bringing the said positive driving means into operation; means for positively driving the stripping roller simultaneously with the driving of the adhesive-applying roller; means for varying the speed of the adhesive-applying roller in accordance with the size of the article being covered; and means for bringing the adhesive-applying roller quickly to rest.

44. In a banding machine the combination of a receptacle for the adhesive substance; an adhesive-applying roller partly immersed in the contents of the receptacle and adapted to be rotated therein; a stripping roller adapted to rotate with its peripheral face clear of the adhesive in the receptacle and a short distance from the adhesive-applying roller; means for positively driving the adhesive-applying roller; means,

acted upon by the band, for bringing the said positive driving means into operation; means for positively driving the stripping roller simultaneously with the driving of the adhesive-applying roller; means whereby the speed of the adhesive-applying roller is varied, during the covering of each article, in accordance with the sizes of the sides of the article being covered; and means for bringing the adhesive-applying roller quickly to rest.

45. In a banding machine the combination of a receptacle for the adhesive substance; an adhesive-applying roller partly immersed in the contents of the receptacle and adapted to be rotated therein; a stripping roller adapted to rotate with its peripheral face clear of the adhesive in the receptacle and a short distance from the adhesive-applying roller; means for positively driving the adhesive-applying roller; means, acted upon by the band, for bringing the said positive driving means into operation; means for positively driving the stripping roller simultaneously with the driving of the adhesive-applying roller; means for varying the speed of the adhesive-applying roller in accordance with the size of the article being covered; means whereby the speed of the adhesive-applying roller is varied, during the covering of each article, in accordance with the sizes of the sides of the article being covered; means for engaging with the band said means being adapted to lift the band clear of the adhesive-applying roller; and means for preventing the positive driving-mechanism for operating while the band is being lifted clear of the adhesive-applying roller.

46. In a banding machine the combination of a main frame; a receptacle for an adhesive substance said receptacle being mounted upon the main frame; an adhesive-applying roller partly immersed in the contents of the receptacle and adapted to be rotated therein; a starting device comprising arms pivotally mounted upon the main frame and means, carried by the arms, for engaging with the band; a friction disk rotatably mounted upon the main frame; means for driving the said friction disk continuously at a uniform speed; a differential disk mounted upon the main frame to rotate with its face opposite that of the uniformly driven disk; an intermediate disk adapted to run with its periphery in contact with the adjacent faces of the differential and the uniformly driven disks and to transmit rotary motion from the latter to the former the said intermediate disk being adjustable radially of the two contacting disks; and intermediate mechanism for transmitting rotary motion from the differential disk to the adhesive applying roller the said intermediate mechanism comprising a swinging frame upon which the starting device rests,

a gear wheel carried by the said frame, a brake shoe against which the said gear-wheel rests when in its inoperative position, and means whereby, when the starting appliance is moved upon the end of the band being pulled, the said frame is swung to bring its gear wheel into engagement with other units of the intermediate mechanism to complete the train between the differential disk and the adhesive-applying roller.

47. In a banding machine the combination of a main frame; a receptacle for the adhesive substance; an adhesive-applying roller partly immersed in the contents of the receptacle and adapted to be rotated therein; a starting device comprising arms pivotally mounted upon the main frame and means, carried by the arms, for engaging with the band; a rotatable member mounted upon the main frame; means for imparting continuous motion to the said member; and intermediate mechanism for transmitting rotary motion from the continuously driven member to the adhesive-applying roller the said intermediate mechanism comprising a swinging frame upon which the starting device rests, a gear wheel carried by the said swinging frame, a brake shoe against which the said gear-wheel rests when in its inoperative position, and means whereby when the starting device is rocked through the pulling of the band end the gear-carrying frame is swung into engagement with other units of the intermediate gear to complete the train of gearing between the continuously driven member and the adhesive-applying roller.

48. In a banding machine the combination of a main frame; a receptacle for an adhesive substance said receptacle being mounted upon the main frame; an adhesive-applying roller partly immersed in the contents of the receptacle and adapted to be rotated therein; a starting device comprising arms pivotally mounted upon the main frame and means, carried by the arms, for engaging with the band; a friction disk rotatably mounted upon the main frame; means for driving the said friction disk continuously at a uniform speed; a differential disk mounted upon the main frame to rotate with its face opposite that of the uniformly driven disk; an intermediate disk adapted to run with its periphery in contact with the adjacent faces of the differential and the uniformly driven disks and to transmit rotary motion from the latter to the former the said intermediate disk being adjustable radially of the two contacting disks; intermediate mechanism for transmitting rotary motion from the differential disk to the adhesive applying roller the said intermediate mechanism comprising a swinging frame upon which the starting device rests, a gear wheel carried by the said swinging

frame, a brake shoe against which the said gear wheel rests when in its inoperative position, and means whereby, when the starting appliance is moved upon the end of the band being pulled, the gear-carrying frame is swung into engagement with other units of the intermediate mechanism to complete the train between the differential disk and the adhesive-applying roller; a rotatable table support for the article to be covered; means for driving the said support; and means whereby the position of the intermediate disk is regulated automatically from the support for the article so that the speed transmitted to the adhesive applying roller varies in accordance with the length of the side of the article being covered.

In testimony whereof I have affixed my signature in presence of two witnesses.

JOHN WILLIAM NASMITH.
